1

The present invention relates to electric apparatus and more particularly an electronic flash device suitable, among other purposes, for photographic illumination.

An electronic flash device includes a tube in which light is produced by a discharge of electric current between electrodes of the tube. Generally the electric energy for the flash is obtained from an alternating current supply stepped up to a higher voltage by means of a transformer, then rectified by a uni-directional conductor to produce pulsating direct current.

The amount of light produced by any specific tube construction depends to a great extent upon the amount of energy in the discharge, and, thus, is directly proportional to the charge in the storage capacitor.

It is important, particularly when the flash device is used for photographic work, that the discharge be uniform in nature so that dependable exposures may be obtained under various conditions without the need of experimentation. Furthermore, the uniform results must be obtainable irrespective of changes in the main electrical supply such as caused by frequency or voltage variation. In addition, when the flash device is of high capacity and the main supply is of comparatively low surge capacity, it is important that the flash device have a controlled charging rate so as to prevent system disturbances and to prevent possible damage to the low capacity supply source. In addition, when excessive peak currents are drawn from a low capacity source, the terminal voltage will drop excessively thereby causing the malfunctioning of components of the device such as relays, time delay devices, etc.

Heretofore the control systems for charging large banks of electrical capacitors for the flash devices have depended upon series impedances in either the primary or secondary circuits to control the rate of current flow into the capacitor. In such a system, in charging the capacitor from the discharged state, the current flow into the capacitor from the source starts at a peak current rate controlled by the series impedance and then decays exponentially as the charge is accumulated.

In such a system when it is necessary that the charging period be very short and the power demand high, the instantaneous current required, in many cases, exceeds the capabilities of the normally available and economically feasible power supply. Another difficulty arises from the fact that the charge stored in the capacitors is in direct relationship to the input volt-

2

age, and since energy storage is proportionate to the square of the voltage, a small variation in input voltage results in a relatively large proportionate variation in energy storage. Another difficulty, with such systems, is that a shift in frequency of the input voltage will effect a change in the value of the series impedance and thereby affect the rate of charge of the capacitors.

This invention aims to overcome the foregoing difficulties and disadvantages by providing an electronic flash device in which the charging current is practically constant or linear and in which the capacitor is automatically charged to its predetermined desired voltage irrespective of variations in supply system conditions.

Another object of the invention is to provide an electronic flash device which is simple and economical in manufacture, efficient in operation and durable in use.

20 In accordance with the invention the foregoing objects are accomplished by providing an electronic charging device including regulating means for the control of its rate and amount of charge. The controlling means includes a saturable reactor bridge for the grid circuit of the rectifier, the reactance of the bridge component being controlled by direct current supplied in variable amount to one or more direct current windings thereon dependent in amount upon one 15 or more conditions which may vary or for which control is desired such as the supply voltage or frequency shift, the peak value of current to be drawn by the capacitor under charge, or the amount of charge.

25 30 35 The construction in accordance with the invention is advantageous for use in systems of comparatively low supply capacity such as portable motor generator units as a comparatively large amount of energy may be stored in the capacitor in a short time by eliminating the peak demand and working the supply over a longer period at a continuous demand within its safe output limit. Furthermore, the control of energy level may be held to very close tolerances not heretofore available.

40 45 50 Other objects and advantages of the invention will be apparent from the following description and from the accompanying drawings which show, by way of example, an embodiment of the invention.

55 In the drawings:

Figure 1 is a schematic wiring diagram of an electronic flash device in accordance with the invention.

Referring to the drawings there is shown in

Figure 1 an electronic flash device in accordance with the invention and including a transformer 2 adapted to be connected to an alternating current source to supply grid-controlled thyratrons tubes 3 and 4 to provide full wave rectification to a supply capacitor 5 for a flash tube 6. The discharge of the capacitor 5 is controlled by a trigger circuit generally indicated by numeral 7. The control circuit 8 for the thyratrons 3 and 4 is used to regulate the charging of the capacitor 5.

The transformer 2 is provided with a primary winding 10, a filament supply winding 11 and a secondary winding 12 having a midtap 13 and outer terminals 14 and 15. By reason of the use of the control circuit later described the transformer may be designed with low impedance in order to provide good regulation.

The thyratrons 3 and 4 may be of the type known as 5563 and are gas filled and, respectively, have cathodes 16 and 17 heated by the filament transformer winding 12 through leads 19 and 20. The tubes are controlled by grids 21 and 22 interposed between the cathodes 16 and 17 and anodes or plates 24 and 25. By reason of the construction of the tubes 3 and 4 they are adapted to pass current from their cathodes to their anodes upon the application of a suitable grid potential.

In order that full wave rectification may be had for the charging of the capacitor 5, the transformer secondary terminals 14 and 15 are connected to the plates 24 and 25 by connecting wires 26 and 27 and the cathodes 16 and 17 are connected to lead 29. The midpoint 13 of the transformer secondary 11 is connected to one terminal of the capacitor 5 by a wire 30, the other terminal of the capacitor being supplied by the wire 29.

A negative bias for the grids is provided by a battery 31 across which is connected a potentiometer 32. A series resistor 33 is connected in the lead 34 to the cathode circuit. The potentiometer has its adjustable arm connected to midpoint 35 of a peaking transformer 36 by a lead 37. Terminals 39 and 40 of the peaking transformer 36 are respectively connected to the grids 21 and 22 by leads 41 and 42 through resistances 44 and 45.

The transformer 10 may be of any desired type suitable to withstand the voltage of the applied circuit and having a rating sufficient to recharge the storage capacitor 5 in the required period of time. The capacitor is connected to electrode terminals 46 and 47 of the tube 6 by wires 49 and 50.

The flash tube 6 may be of the type known as an FT500 and is made with a glass envelope 51 which is gas filled with xenon or other suitable gas, the electrodes 46 and 47 extending into the gas filled chamber. A triggering electrode 52 is wound about the envelope 51 of the tube 6 and is adapted when a voltage surge or pulse of electricity is applied to initiate ionization of the gas within the envelope 51, thus causing it to become a conductor and permitting the capacitor 5 to discharge between the electrodes 46 and 47.

The trigger circuit 7 includes a cold cathode tube 55 of the type known as SN4 having electrodes 56 and 57 and grids 59 and 60. A direct current power supply is taken from a battery 61 by the leads 62 and 64. The electrode 57 is connected to the supply lead 64 by a common connection 58 and to a resistor 65 having its other terminal connected to the grid 60. A capacitor

66 is connected at one terminal to the grid 60 and its other terminal to a resistor 67 through a lead 68 then to the electrode 56 by a lead 64. The supply lead 62 is connected to the grid 59 with a resistor 69 therebetween. Another resistor 70 is connected between the grid 59 and the electrode 56 by a lead 71.

A triggering transformer 74 has one terminal of its secondary 75 connected to the triggering electrode 52 by a lead 76 and its other terminal connected to the supply wire 50 from the capacitor 5 by a lead 77. The primary 79 of the trigger transformer 74 has one lead connected to the common connection 58 between the main electrode 57 and the resistor 65 by a wire 80. The other terminal of the primary winding 79 is connected by a wire 81 to a capacitor 82 in turn connected by a lead 84 to the electrode 56. A switch 90 is connected across the wires 58 and 68 for single flashing of the tube 6. In addition, for alternative use, for the successive flashing of the tube 6, a multicontact switch 91 is connected in parallel with the switch 90. The switch 91 has a plurality of contacts 92 adapted to be swept by a spring urged midpoint 93 in any suitable construction to provide a succession of contact of successive make and break connections between the wires 58 and 68 the switch having a time contact to provide a delay between successive contacts to allow the deionization of the tube 6, and may be of the type commonly used for telephone machine switching.

The operation of the trigger tube circuit is well known in the art and is initiated by a momentary pulse applied to the grid 60. In the static condition the voltage of power supply 61 is applied across the cold cathode tube 55 and the capacitor 82 which is charged to the full voltage of the power supply 61. Likewise capacitor 66 is charged through resistors 65 and 67 to the same voltage. The grid 59 is biased to a positive voltage with respect to cathode 57 by the proper ratio of voltage drops across the resistors 69 and 70. Grid 60 is maintained at the same potential as the cathode 57 as it is connected through resistor 65 through which there is no current flow.

When the trigger pulse is desired, terminal 68 is connected to the cathode 65 by actuation of either the switch 90 or, if successive pulses are desired, by actuation of the multiple contact switch 91. At the instant that terminal 68 of the capacitor 66 is connected to the cathode 57 by one or the other of the switches 90 or 91 the full voltage of the capacitor appears across the resistor 65 thereby applying a voltage pulse to the grid 60. This voltage pulse ionizes the gas in the cold cathode tube 55 allowing the capacitor 82 to discharge through the primary winding 79 of the triggering transformer 74. The discharge of the capacitor 82 through the primary winding 79 induces a high voltage pulse in the secondary winding 75 which, in turn, ionizes the gas in the flash tube 51.

The control circuit for the thyratrons 3 and 4 is based on a bridge 100 incorporating saturable reactances 101 and 102 in a bridge connection with resistances 103 and 104. The output of the bridge 100 is connected to the peaking transformer 36 by wires 105 and 106. The bridge 100 is supplied from the alternating current source by a transformer 110 having a primary winding 111 and a secondary winding 112. The secondary winding 112 has a first terminal connected to a phasing capacitor 114 by a lead 115, the other terminal of the capacitor being con-

nected to one terminal to the bridge 100 by a wire 116. The second terminal of the transformer secondary 112 is connected to the bridge by a wire 117. The phase shifting capacitor 114 is of a capacity value chosen initially to adjust the phase of the output voltage of the bridge 100 approximately 180 degrees lagging the voltage on the plates of the thyratrons 3 and 4. By varying the impedance of the reactance arms, the phase of the voltage applied to the peaking transformer is gradually moved ahead depending upon control information which may be applied to the bridge from the various components of the circuit and which may be responsive to circuit conditions. Variations in frequency are controlled by the circuit generally indicated at 120, while rate of charge and maximum voltage of charge are regulated by the circuit 121.

The reactive legs 101 and 102 of the bridge 100 are exactly similar in construction and are made with iron cores each having thereon one of the main alternating circuit windings 101 or 102 and in addition direct current windings numbered 130 through 133 while the other has direct current windings 134 through 137. By means of the direct current windings a controlled direct circuit flux may be applied to the core to vary the effective inductance of the bridge leg. Series connections between the pairs of windings are provided between windings 130—137 by wire 140, between windings 131 and 136 by wire 141, between windings 132 and 135 by wire 142, and between windings 133 and 134 by wire 143. Terminal connection means are provided by wires connected from the outer terminals of the series coils to terminals numbered 150 through 157. The terminals 150 and 151 being the terminals of the series connected coils 130 and 131, terminals 152 and 153 being the terminals for the series connected coils 131 and 136, terminals 154 and 155 being the terminals for the series connected coils 132 and 135 and terminals 156 and 157 being for the series connected coils 133 and 134. In order to provide a direct current reference flux, the windings 133 and 134 are connected to the direct current source of supply by wires 160 and 161 connected respectively to terminals 156 and 157. A series adjustable resistor 162 is connected in series with wire 160 and thence by wire 163 to the direct current supply 61. The frequency control circuit 120 is supplied from the alternating current source by wires 170 and 171 and includes an inductance 173 connected between the lead 170 through a lead 173a to a terminal 174 of a rectifying bridge 175 having four rectifiers 176—179 connected in a bridge circuit. The alternating current input to the bridge 175 is through the terminals 174 and 180. Rectified direct current is taken from the terminals 181 and 182 and supplied by wires 184 and 185 to the terminals of a shunting capacitor 186, one terminal of which is connected by a lead 187 to a variable resistance 188 and thence by a wire 189 to one terminal 155 of the direct current series winding 132—135 of the bridge 100. The other side of the capacitor is connected by wire 190 to the other terminal 154 of the direct current winding 132—135. By this circuit there is provided in the control bridge 100 a direct current depending in magnitude upon the frequency of the supply circuit. As the alternating current supplied to the bridge 175 is limited by the inductance 173 which, of course, decreases in value for a decrease in frequency thereby passing an increased direct current to the bridge

which can be connected so as to either add to or detract from the flux of the reference windings 133 and 134.

The rate of charge on the capacitor 5 and the maximum potential applied to the capacitor 5 are determined by the circuit 121 which is controlled by the variation in voltage across the capacitor 5. As the charging potential is applied to the capacitor the voltage across the capacitor will rise from zero as the charge accumulates.

The peak current drawn from the power supply depends on the instantaneous plate voltage at the instant the tube conducts less the voltage on the capacitor divided by the impedance. This can be more clearly defined by the following formula:

$$I \text{ (inst.)} = \frac{E_p - E_c}{Z}$$

Where I is the instantaneous current, E_p is the instantaneous plate voltage, E_c is the voltage across the capacitor and Z is the total impedance of the circuit.

By preventing the thyratron tubes 3 and 4 from firing until the instantaneous plate voltage has decayed to a relatively low value, the peak current is limited when the voltage across the capacitor 5 is zero or at a low value. As the voltage across the capacitor builds up, the point of firing in relation to the voltage cycle applied to the plates of thyratrons 3 and 4 is advanced allowing the tube to fire earlier in the cycle at higher voltage values and for a longer period of time in the cycle. This has the effect of keeping the peak current through the tubes 3 and 4 at a constant value and also of providing a linear average current characteristic. These factors enable the utilization of the supply system to the greatest advantage while at the same time keeping the peak values within the safe limitations of the supply system.

In order to supervise the charging rate and maximum charge on the capacitor 5, a voltage dividing circuit 200 is connected across the capacitor and tapped points are connected by wires 201 and 202 one of which lead 202 leads to the grid 203 of the tube 205 of the type termed 6L6. The cathode 207 is connected through a resistor 208 having a moveable mid-point 209 through wire 210 to terminal 151 of the impedance bridge 100 for the energizing of coils 130 and 137. The return from the coils at 150 is connected by a wire 218 to the negative of battery 216 by a lead 211. The plate 212 of the tube 204 is connected by a wire 214 to the positive terminal of the battery or direct current supply 216. The midpoint 209 of the reactance 208 is connected by wire 220 through a diode tube 221 which may be of a type known as 6H6, thence through a lead 222 to grid 223 of a tube 224 which may be of the type known as 6AG7. The plate 225 of the tube 224 is connected by a wire 226 to terminal 152 for the series connected coils 131—136. The other side of coils 131—136 is connected through terminal 153 by leads 211 and 214 to the positive terminal of battery 216. The connection is made from the grid 223 through a grid leak resistor 227 through a wire 228 to the movable top 229 of a variable resistor 230. One terminal of the resistor 230 is connected to cathode 231 of the tube 224 and also through a wire 232 to one electrode 233 of a voltage regulating tube 234 which may be of the type known as No. VR150. The other electrode 235 of the tube 234 is connected by a lead 236 to the other end of variable resistor 230.

and a tap connection 237 is made to wire 201. By means of the voltage divider 200 a reference voltage is obtained to control the current flow in the appropriate control windings of the reactor bridge. The control is so proportioned that linear current flow is obtained. The voltage across the capacitor 5 is sampled by the voltage divider and carried by wires 201 and 202 to the tube 205 to vary the grid voltage thereof. Tube 205 then acts as a variable resistor which controls the D. C. current through reactance direct current windings 130—131, thereby providing a control through the bridge to the thyatron for the linear charging of the capacitor 5.

While it is desirable to charge the capacitor 5 as rapidly as possible, it is necessary that the voltage applied to the capacitor be cut off at a predetermined point so as to assure uniformity of charge on the capacitor which in turn of course will assure uniformity in the brilliance of the flash from the discharged tube. This could be achieved by taking a voltage signal from the resistor 200 which is in parallel with the capacitor 5. However, it is desirable to achieve greater accuracy in determining the peak voltage than is possible with this method. Therefore, the tube 205, which has been previously used as a current control tube, is used also as an amplifier for the voltage signal from the voltage divider 200. A small change of voltage across the portion of the voltage divider 200 between its two connections *a* and *b* is applied to the grid 204 of the tube 205, thereby causing a change in current through the tube and through the cathode resistor 208. The change in voltage across the resistor 208 is larger than the voltage change between the points *a* and *b* of the voltage divider 200, thus, producing a larger signal in relation to the change of voltage across condenser 5. The amplified voltage signal across 208 is fed through the voltage peak tube 221 into the control tube 224. By reason of its bias, tube 224 is normally cut off and there is no current through control windings 131—136. However, when the voltage across 208 builds up to the point that tube 221 conducts and overcomes the bias of the grid 223 of tube 224, the tube suddenly becomes a conductor and passes a current through the windings 131—136 which offsets the phase advance caused by the current flow through the windings 130—137. Thus, retarding the phase of the potential applied to the grid control thyatron 3 and 4 and thereby stopping further increase in charge on the capacitor 5. The tube 224 is designed with a sharp cutoff and the tube 221 is used in series with the grid 223 to provide a clipping action so as to assure dependable and uniform control accurately limiting the charge on the capacitor 5.

From the preceding description it will be seen that the present invention provides an electronic flash device having efficient and reliable control means for assuring a uniform charge on the capacitor at a control rate such as to prevent supply source disturbances yet such as to assure rapid recharging as may be required for successive flashes.

While the invention has been described and illustrated with reference to a specific embodiment thereof, it will be understood that other embodiments may be resorted to. Therefore, the form of invention set out above should be considered as illustrative and not limited in scope as to the following claims.

I claim:

1. An electronic flash device comprising a flash tube, a capacitor to store energy to flash the tube, a grid-controlled rectifier for charging the capacitor, control means for the rectifier grid including a saturable reactor, a direct current winding for the saturable reactor, a source of direct current, and control means to vary the direct current through the direct current winding, including a feedback circuit obtaining information from across the storage capacitor, whereby the charging rate of the storage capacitor and its maximum voltage is limited to a predetermined value.

2. An electronic flash device comprising a flash tube, a capacitor to store energy to flash the tube, a grid-controlled rectifier for charging the capacitor, control means for the rectifier grid including a saturable reactor, a direct current winding for the saturable reactor, a source of direct current, control means to vary the direct current through the direct current winding including a feedback circuit from the storage capacitor and responsive to the potential thereof, and a frequency sensitive bridge rectifier circuit adapted to provide a varying direct current output responsive to a change of supply frequency, whereby the charging rate of the storage capacitor and its maximum voltage is limited to a predetermined value.

3. An electronic flash device comprising a flash tube, a capacitor to store energy to flash the tube, a grid-controlled rectifier for charging the capacitor, control means for the rectifier grid including a reactor bridge, and direct current control means for the reactor bridge responsive to electrical information from across the storage capacitor to control the rate of charge thereon.

4. An electronic flash device comprising a flash tube, a capacitor to store energy to flash the tube, a grid-controlled rectifier for charging the capacitor, control means for the rectifier grid including a reactor bridge, and direct current control means for the reactor bridge responsive to potential of the capacitor to control the rate of charge and peak voltage thereon.

5. An electronic flash device comprising a flash tube, a capacitor to store energy to flash the tube, a grid-controlled rectifier for charging the capacitor, negative bias means for the rectifier grid, and a reactor bridge adapted to act in opposition to the negative bias to render the rectifier operative and the bridge variable to control the energy stored in the capacitor.

6. An electronic flash device comprising a flash tube, a capacitor to store energy to flash the tube, a grid-controlled rectifier for charging the capacitor, negative bias means for the rectifier grid, and an alternating current bridge adapted to act in opposition to the negative bias to render the rectifier operative, and direct current control means for the bridge responsive to circuit information to shift the output of the bridge to control the energy stored in the capacitor.

7. An electronic flash device comprising a flash tube, a capacitor to store energy to flash the tube, a grid-controlled rectifier for charging the capacitor, negative bias providing means for the rectifier grid, a reactor-resistor bridge connected to supply a grid potential to act in opposition to the reactor, grid negative bias, and direct current windings for the reactors of the bridge to shift the phase angle of the bridge bias voltage with respect to the rectifier anode-cathode volt-

age to vary the charge on the capacitor to control the energy stored in the capacitor.

8. An electronic flash device comprising a flash tube, a capacitor to store energy to flash the tube, a grid-controlled rectifier for charging the capacitor, negative bias providing means for the rectifier grid, a reactor-resistor bridge connected to provide a grid potential to act in opposition to the reactor, grid negative bias, a first set of direct current windings for the reactors of the bridge to provide a reference direct current flux, and a second set of direct current windings for the reactors responsive to circuit information to control the energy stored in the capacitor and thus to control the energy of the flash.

9. An electronic flash device comprising a flash tube, a capacitor to store energy to flash the tube, a grid-controlled rectifier for charging the capacitor, negative bias providing means for the rectifier grid, a reactor-resistor bridge connected to provide a grid potential to act in opposition to the reactor, grid negative bias, a first set of direct current windings for the reactors of the bridge to provide a reference direct current flux, a second set of direct current windings for the reactors, a direct current information source including an inductance, and a rectifier bridge having its input bridge connected in series with the inductance the output of the bridge connected to the second set of direct current windings to provide direct current flux to act with the reference direct current flux to vary the charge on the capacitor to control the energy stored in the capacitor and thus to control the energy of the flash irrespective of system frequency variations.

10. An electronic flash device comprising a flash tube, a capacitor to store energy to flash the tube, a grid-controlled rectifier for charging the capacitor, negative bias providing means for the rectifier grid, a reactor-resistor bridge connected to provide a grid potential to act in opposition to the reactor, grid negative bias, a first set of direct

current windings for the reactors of the bridge to provide a reference direct current flux, a second set of direct current windings for the reactors, a direct current information source including a potentiometer connected across the capacitor to provide a source of potential drop, and electronic control means to control current through the second windings responsive to said potential drop to provide a flux to coat with the reference flux to provide a grid voltage shift to control the rate of charge of the capacitor.

11. An electronic flash device comprising a flash tube, a capacitor to store energy to flash the tube, a grid controlled rectifier for charging the capacitor, negative bias providing means for the rectifier grid, a reactor-resistor bridge connected to supply a grid potential to act in opposition to the negative bias, a first set of direct current windings for the reactors of the bridge to provide a reference direct current flux, a second set of direct current windings for the reactors, a direct current information source including a voltage divider connected across the capacitor to provide a source of potential drop, electronic amplifying means responsive to said potential drop to provide an amplified control voltage, and electronic control means responsive to said amplified voltage to provide a flux to coat with the reference flux to cause the rectifier to limit the charge on the capacitor to a predetermined value and thus to control the energy of the flash.
